FIG. I

FIG.2

To all whom it may concern:

Be it known that we, Wilhelm Hektor Paul and Eugen Friedrich Trenkle, both German citizens, and both residing at Furtwangen, Black Forest, Germany, have invented a new, original, and ornamental Design for a Clock, of which the following is a specification, reference being had to the accompanying drawings, forming a part thereof.

In the drawings:

Fig. 1 is a front elevation of a clock showing our new design.

Fig. 2 is a side elevation thereof on a larger scale.

We claim:

The ornamental design for a clock, substantially as shown.
